MEANS FOR TWISTING AND WINDING
ARTIFICIAL FILAMENTS

Harry Clement Curtis, Morecambe, England, assignor to Cellulose Acetate Silk Company, Limited, Lancaster, England, a company of Great Britain and Northern Ireland

Application March 16, 1931, Serial No. 522,957
In Great Britain September 4, 1930

2 Claims. (Cl. 118—69)

This invention relates to improvements in the manufacture of artificial threads or filaments or the like, either by the dry or wet spinning process.

5 It is general, in the manufacture of artificial silk, to either collect the filaments (a) in parallel form, or (b) in twisted form. The latter has the advantage over the former in that the threads may not require any further twisting 10 previous to further manufacturing process or operations.

This invention particularly relates to the particular method of collecting the filaments in twisted form known as ring spinning.

15 The difficulty in the twisting and winding of artificial filaments by means of the ring spinning process has hereto been that the threads or filaments are extruded, and paid out by the godet roller at such a high speed that some difficulty is found in getting the thread under the traveller and in applying the thread to the bobbin, without fouling the machinery with an accumulation of loose filaments or threads.

I am aware that various devices have been invented for overcoming this difficulty (see 20 British specifications Nos. 293,371, 323,812 and 9,984/1930).

The present invention describes two distinct methods of performing the same operation, with 25 the use, in one case, of the waste roller, and in the second case, without any additional device whatsoever. Thus, it has the advantage of enabling the ring spinning method of twisting and winding to be used without the use of any extra 30 apparatus and without temporary stoppage of the spindle, whilst threading the traveller, as it is necessary in the case of other devices, the proper twist being obtained immediately as soon 35 as the thread is thrown onto the bobbin.

40 According to this invention, I provide a loose ring surrounding the bobbin and resting on a bracket, characterized by a traveller partly surrounding the ring section, and placed in a radial plane, adapted to receive the threads, filaments 45 or the like, said ring being provided with two identical notches adapted to engage corresponding smooth cylindrical (that is, headless) steady pins on the bracket, and being thereby prevented from rotating when resting on the said bracket.

Referring to the drawing left herewith which 50 illustrates as examples, some manners of carrying out the invention, without limiting the latter to these examples:

Fig. 1 shows in side elevation the whole ap-

paratus (the ring being in section) and the traveller, together with the waste roller;

Fig. 2 shows the loose ring in section, with the traveller threaded;

Fig. 3 shows the thread being drawn through 80 the loose ring by hand;

Fig. 4 shows the spindle and bobbin in front elevation with the loose ring resting on its brackets or steady pins;

Fig. 5 shows a plan of the device;

Fig. 6 shows the bobbin in side elevation, the loose ring being shown in section, and illustrates the alternative method for applying the thread to the bobbin without the waste roller.

In Fig. 1, the untwisted filaments (2) run 70 round the godet roller (1) over the guide (9), through the traveller (5), and then on to the waste roller (10); (3) is a steady pin for keeping the loose ring in position; (4) is a loose ring, and (6) is a bracket for carrying the loose 75 ring; (8) represents the means on which the spun thread is collected. This may be in the form of bobbin or spool or any other suitable collecting device.

The method of applying the thread to the 80 bobbin or collecting device is as follows:—

The yarn, while it is run on the waste roller 85 (10) is pressed on the bottom flange of the collecting device by means of a piece of rod (7), which may be of any suitable material. On touching the moving lower flange of the 90 bobbin, the yarn breaks at (7) and begins to wind on the bobbin or the like.

Fig. 2 shows the loose ring which has been 95 lifted off the bracket (6) and the method of passing the thread through the traveler (5). The traveler may be of any design. The ring may or may not be supplied with two diametrically opposite raised portions constituting finger pieces (15) (Fig. 5), for conveniently holding 100 the said ring.

Fig. 3 shows the loose ring which is still off its bracket, and the method of passing the thread through the ring by means of the operator's finger (11).

The ring is then replaced on to its bracket as shown in Figs. 4 and 5, and the thread is run on to the waste roller (10). The collecting device is then placed on the spindle (14) and the yarn then placed on to it as already 105 described.

Alternatively, if it is desired to dispense with the waste roller as shown in Fig. 6, the thread 110 (2) is drawn in the form of a loop from the godet roller and threaded on the traveler in the

manner described with reference to Figs. 2 and 3. The ring through which the thread is looped as shown in Fig. 3 is then held by the operator in his free hand in any convenient position on 5 the steady pins while the thread (2) takes up the position as shown in Fig. 6. The thread (2) is caused to touch the moving bottom flange of the collecting device; the thread immediately breaks at the point of contact and begins to 10 twist and wind on the collecting device. As soon as this begins the loose ring is replaced on to its bracket (6) and the operation proceeds.

The characteristics of this invention are (1) the use of a loose ring, with or without finger 15 pieces; (2) the superfluity of any help from other threads, loops, rollers or hooks, except when a waste roller is used; (3) there is no need to stop the collecting device in order to start up the twisting and winding.

20 What I claim and desire to secure by Letters Patent is:—

1. In machinery of the so-called "ring" type, for twisting and winding artificial threads, filaments or the like, a bobbin, a bracket mounted in 25 operative relation to said bobbin, smooth cylindrical (that is, headless) steady pins on the said bracket, a loose ring surrounding said bobbin and capable of resting on the said bracket, notches in said ring adapted to engage said 30 steady pins on the bracket, a traveler, partly

surrounding the ring section of said loose ring and placed in a radial plane, being adapted to receive the threads, filaments or the like, and the said loose ring, while being prevented by the steady pins from rotating when resting on the said bracket, being capable of being swiftly lifted vertically free from the rail plate, without preliminary lateral displacement.

2. In machinery of the so-called "ring" type, for twisting and winding artificial threads, filaments or the like, a bobbin, a bracket mounted in operative relation to said bobbin, smooth cylindrical (that is, headless) steady pins on the said bracket, a loose ring surrounding said bobbin and capable of resting on the said bracket, notches in said ring adapted to engage said steady pins on the bracket, a traveller, partly surrounding the ring section of said loose ring and placed in a radial plane, being adapted to receive the threads, filaments or the like, the said loose ring, while being prevented by the steady pins from rotating when resting on the said bracket, being capable of being swiftly lifted vertically free from the rail plate, without preliminary lateral displacement and provided with two diametrically opposite raised portions constituting finger pieces for conveniently holding said ring.
